COUNTER FLOW AIR CONDITIONER

Lester U. Larkin, Atlanta, Ga., assignor to Larkin
Refrigerating Corporation, Atlanta, Ga., a cor-
poration of Georgia

Application November 16, 1933, Serial No. 698,291

2 Claims. (Cl. 257—244)

This invention relates generally to ventilating air cooling systems; and, more particularly to cooling systems adapted for use in the form of small compact highly efficient units for cooling air in refrigerated display counters or cases, market refrigerators, cold storage rooms, and the rooms of residences, office buildings, etc.

In residence and office cooling it is ordinarily desirable to decrease the humidity of the air as it passes through the conditioner; since, a decrease in humidity results in a greater rate of evaporation of perspiration in the persons subjected to the conditioned air. In this case, the cooling unit is comparatively small, and the temperature difference is likewise comparatively small, since comfortable living conditions never require the air to be lowered anywhere near the freezing point. In other words, a small cooling unit circulating hot humid air will decrease the humidity thereof.

On the other hand, a comparatively large unit used for refrigeration purposes in a cooler or cold storage room may cause an increase in relative humidity, since the conditioned air is usually brought down to temperatures around the freezing point. This refrigeration, obviously, causes shrinkage of the air originally in the cooler, and with a consequent suction of outside air, and its moisture content, into the cooler to compensate for this shrinkage. This results in an increase in relative humidity of the air in the cooler. This means that decrease or increase in humidity of a compartment or room will depend upon the size of the cooling unit as compared with the size of said compartment or room, and with the drop in temperature which the unit is designed to effect.

The main object of the invention, therefore, is to provide an air conditioning unit which is highly efficient in operation, and in which the relative humidity of the air conditioned may be considerably increased by the cooling operation of the unit, or may be decreased where this is found necessary or desirable.

Other objects of the invention will become apparent as the detailed description thereof proceeds.

In the drawings:

Figure 1 is a top plan view of an air conditioning unit embodying the present invention, part of the casing being removed to illustrate details of construction;

Figure 2 is a vertical section taken on the line 2—2 of Figure 1;

Figure 3 is a top plan view, similar to Figure

1, showing a modified form of the invention; and Figure 4 is a vertical section taken on the line 4—4 of Figure 3.

In Figures 1 and 2 of the drawings, the unit is shown as comprising a base plate 1, extended rearwardly to form a support 2 for a motor 3 having its rotor shaft 4 extending in opposite directions from the motor casing. On each side of the motor there are arranged the blower casings 5 and 6 constructed to communicate at their upper ends with the conduit 7 forming part of an air cooling casing designated generally by the numeral 8.

The casing 8 comprises the base plate 1, side walls 9 and 10, a top 11 and partitions 12 and 13 extending across the casing parallel to the base plate 1 and dividing the casing into three conduits 7, 14 and 15. The conduits 7, 14 and 15 are substantially equal in size, and are dimensioned so that each conduit can accommodate at least two grids of a cooling coil formed of piping having an outlet 16 at the warm air inlet of the conduit 7. The top 11 is connected to the partition 13, at the exit end of the casing 8, by a semi-cylindrical casing 17; and the base plate 1 is likewise connected by a semi-cylindrical plate 18 to the motor end of the partition 12. By this arrangement, the conduits 7, 14 and 15 form a continuous counterflow duct for conducting air from the air inlet 19 of the unit to the air outlet 20 thereof.

As will be apparent from the drawings, the piping forming the upper grid in the conduit 7 extends from the refrigerant outlet or suction connection 16 to the exit end of the casing 8. At this exit end, a bend 21 connects the upper grid 22 to the lower grid 23 in the conduit 7. The lower grid 23 at the inlet end of the casing 8 is connected by a bend 24, which extends through the partition 12, to the upper grid 25 in the conduit 14. At the exit end of the casing 8, which is also the inlet end of the conduit 14, the upper grid 25 is connected by a bend 26 to the lower grid 27 in the aforesaid conduit 14.

At the inlet end of the casing 8, the grid 27 is connected by a bend 28, passing through the partition 13, with the grid 29 in the upper part of the conduit 15. The grid 29, at the exit end of the casing 8 and of the conduit 15, is connected by a bend 30 to the lowermost grid 31, which, at the inlet end of the casing 8, is connected to the inlet end 32 of the entire coil system contained within the several conduits 7, 14 and 15.

It will be noted from the foregoing disclosure that the warm air forced into the conduit 7 by

the blowers contacts with the warmest part of the cooling coils. This construction and mode of operation enables the refrigerant to absorb the greatest number of heat units possible for it to contain at temperatures prevailing at the exit or suction end thereof. In this respect, the present cooling unit operates directly opposite to the cooling devices of the prior art. In other words, the warm air contacts the warmest part of the 10 coil; and the cold or conditioned air emerges from the coldest end of the unit.

This arrangement and mode of operation have the effect of reducing or practically eliminating condensation. It is obvious that the nearer the 15 temperature of the coil to that of the air impinging thereon, the less will be the condensation. This effect continues throughout the entire length of the conduits from inlet to exit. In other words, the decrease in temperature of the air being conducted through the air ducts of the unit is effected gradually and not in sharp steps as would be the case if the warm air were forced initially against the coldest part of the coil system to emerge at the warm end thereof.

25 The grids of each compartment are traversed by a series of fins 33, preferably of aluminum, and extending perpendicularly to the convolutions of the grids in each compartment. These fins are preferably constructed and arranged on 30 the grids substantially as disclosed in the United States patent to Larkin, No. 1,776,235, September 16, 1930; and each extends substantially the entire length of the conduit in which it is arranged.

35 As disclosed in the aforesaid Larkin patent, the coils provided with these vertical fins are highly efficient and reduce the temperatures of air passing therethrough with great rapidity. Moreover, the temperature differential between 40 the coils and the air conditioned thereby is so small that to bring the air down to any desired temperature, it is only necessary to maintain the refrigerant inlet end of the coil at about one degree below that of the air as it emerges from 45 the exit end of the unit.

It must be distinctly understood that this invention is not to be considered as in anyway limited to the number of air conduits arranged in the casing, or to the number of grids of cooling coils which may be arranged in each conduit. It must also be understood that the invention is not to be considered as limited to the use of any particular number of cooling grids in each conduit. It is desirable, of course, that the coldest 55 end of the coils shall be at the exit end of the casing. This result could obviously be obtained by using three grids zigzagged in the conduit 15. However, the final result is not substantially affected by using the two grids as shown in conduit 15, and which, therefore, require the cold inlet end of the coil system to be positioned at the warm air end of the unit. In the ideal system, however, the cold inlet of the cooling coils should be located at the cooled air exit.

65 In the modification shown in Figures 3 and 4, the blower mechanism and casing are substantially the same as the blower mechanism and casing shown in Figures 1 and 2; and the corresponding parts thereof are designated by the

same reference characters. In this form of the invention, however, the refrigerant inlet 32' of the coil piping 35 terminates at the cold air outlet 20' of the unit. The coil construction in this form of the invention will be obvious from inspection of the drawings.

It is intended that either of the units disclosed in this application may be used in any convenient position. For example, either unit may be installed with its conduits perpendicular in one end 10 of a refrigerated counter. The unit may be arranged with a motor at the bottom of the counter so as to expel cold air out of the top of the unit toward the center of the refrigerator in which case it may be convenient to use a duct extending 15 from the outlet of the unit along the top of the counter case. The unit may also be disposed with the motor and fans below the top of the counter to expel the cold air toward the center of the case and along the bottom thereof. 20 In other words, the operation of the invention disclosed herein is not in any way dependent upon its being arranged in any particular position in any refrigerator or compartment.

25 While not shown nor described in this application, it is to be understood that the unit will be provided with the usual adjustable thermostatic controls to regulate the operation of the refrigerant coils and the temperature of the air conditioned by the unit. These thermostatic 30 switches and valves controlled thereby are very well known in this art; and form no essential part of the present invention.

35 It is thought that the invention and numerous of its attendant advantages will be understood from the foregoing description, and it is obvious that numerous changes may be made in the form, construction and arrangement of the several parts without departing from the spirit or scope 40 of my invention, or sacrificing any of its attendant advantages, the form herein described being a preferred embodiment for the purpose of illustrating my invention.

45 What I claim is:

1. An air conditioner comprising: a casing having a series of superposed conduits extending lengthwise therethrough, means for connecting the adjacent ends of said conduits in series to provide a continuous circuitous air duct through all of said conduits, means for forcing air through 50 said duct, means extending transversely of each conduit for cooling the air during its passage through said air duct, and cooling fins extending lengthwise of each conduit in said air duct and connected to said air cooling means. 55

2. An air conditioner comprising: a casing having a series of superposed conduits extending lengthwise therethrough, means for connecting the adjacent ends of said conduits in series to provide a continuous circuitous air duct through all of said conduits, a refrigerating coil grid mounted in said casing and having grid branches extending substantially across each of said conduits, and cooling fins extending lengthwise of each conduit and in heat conducting contact 60 across said branches. 65

LESTER U. LARKIN.
